UNITED STATES PATENT OFFICE.

GEORGE JONATHAN FORREY, OF CARLISLE, ASSIGNOR OF ONE-HALF TO
JOHN W. JOHNSON, OF READING, PENNSYLVANIA.

NUT-MACHINE.

SPECIFICATION forming part of Letters Patent No. 432,522, dated July 22, 1890.

Application filed March 19, 1890. Serial No. 344,514. (No model.)

To all whom it may concern:

Be it known that I, GEORGE JONATHAN FORREY, a citizen of the United States, residing at Carlisle, in the county of Cumberland and State of Pennsylvania, have invented a new and useful Nut-Machine, of which the following is a specification.

This invention has relation to that class of metal-working machines employed for the stamping and otherwise forming of nuts and washers; and among the objects in view are to provide a machine for the above purpose which will automatically stamp and form the nut from a blank of metal, subsequently punch the same, and afterward deliver the nut therefrom, said machine to be provided with suitably-timed mechanism for accomplishing these successive steps.

Other objects and advantages of the invention will hereinafter appear in the following description and will be particularly pointed out in the claims.

Referring to the drawings, Figure 1 is a perspective of a nut-forming machine constructed in accordance with my invention. Fig. 2 is a side elevation, the fly-wheel at that side of the machine being removed. Fig. 3 is a rear elevation. Fig. 4 is a central vertical section. Fig. 5 is a transverse horizontal section through the vertically-sliding head. Fig. 6 is a vertical transverse section through said head and through the bed. Fig. 7 is a detail in perspective of the die-carriage. Fig. 8 is a detail in perspective of the crown-forming die. Fig. 9 is a face view of the cam for operating the rock-shaft which operates the car. Fig. 10 is a perspective in detail of the stamp-guiding plate. Fig. 11 is a detail in perspective of the rear end of the rock-shaft, illustrating the adjustable sliding block. Fig. 12 is a detail of the forming-plate. Fig. 13 is a detail in perspective of the head-operating lever. Fig. 14 is a detail in perspective of the head, the wheels being taken from the rear. Fig. 15 is a detail in perspective of the stamp detached.

Like numerals of reference indicate like parts in all the figures of the drawings.

Upon any suitable base, as 1, there is mounted a pair of vertical standards 2, which have their front ends at their upper portions

slightly overhanging, as at 3, and provided with opposite inclined ways 4, forming a vertical bed for the reception of the stamping and punching mechanism. Passing transversely through the two standards is a shaft 5, suitably secured in position, and mounted pivotally upon the same, so as to freely oscillate, is a lever 6, which terminates at its front end in a toothed sector 7. In rear of the shaft the lever is upwardly and rearwardly disposed and projects slightly beyond the rear edge of the standards. A sliding head 9, of oblong shape, is mounted in the vertical bed at the front end of the standards and has its opposite side edges provided with dovetailed grooves 10 to fit the similarly-shaped ribs located at the sides of the bed. Secured to the rear face of the sliding head is a bracket 11, from which there projects rearwardly a flange 12, the rear edge of which is toothed and is meshed by the teeth of the sector at the forward end of the lever 6. The flange 11 is also provided with a curved slot 13, in which is mounted for sliding a block 14. Opposite straps 15 are rigidly secured to the toothed sector of the lever 6, and their front ends are pivoted, as at 16, to the sliding block 14, so that in the vertical movement given the sliding head by the oscillating lever said block rides within its slot, as will be apparent, and a positive engagement of the teeth of the sector with the teeth of the head is insured.

Bearing-blocks 17 are secured opposite each other to the rear edges of the standards 2, and in the same there is journaled a crank-shaft 18, provided at its center between the standards with a cranked portion 19. The ends of the shaft beyond the standards each carry large fly-wheels 20, and at one side of the machine and outside of the adjacent standard carries a bevel-gear 21, spaced from the adjacent fly-wheel by a collar 22. Between the centrally-cranned portion and the bearing at the same side of the standards there is located a gear 23. Below the bearing-blocks 17 there is located a second pair of bearing-boxes 24, in which is mounted a crank-shaft 25, provided at one side of its center with an ordinary cone-pulley 26 and at the other side with a gear 27, which latter

meshes with the gear 23 of the crank-shaft. A belt 28 leads from the cone-pulley to any suitable motor for operating the machinery.

Upon the crank-shaft 19, at what may be termed the "right-hand" side of the machine, or that side opposite the beveled gear 21, is mounted a disk 29, which upon its outer surface is provided with a continuous cam-groove 30. Beyond the disk there is mounted on the shaft a gear 31, which corresponds to the gear 21 at the opposite side of the machine, and the gear 31 and the disk are spaced apart, as shown. A plate 32 is securely bolted to the outer face of the gear, and from the plate there projects outwardly a bearing-bolt 33, carrying a loose roller 34. Outside of the plate 32 and between it and the adjacent fly-wheel 20 is mounted the spacing-sleeve 22.

Upon the upper end of the standards there is mounted a bearing-post 35, provided at its upper end with a bearing perforation, and through the same there passes a bearing-pin 36, upon which is mounted a balancing-lever 38. The balancing-lever 38 is formed in opposite sections, which at their front ends are oppositely flared or spread, and in the forward end of each of said sections there is pivotally connected, as at 40, the upper end of a vertical connecting-bar 41, the lower ends of the bars being pivoted, as at 42, to the upper bifurcated ends of a pair of brackets 43, secured to the upper edge and near the opposite sides of the vertically-sliding head 9. The rear ends of the lever-sections 38 clamp between them the inner end of a poised-beam 44, upon which there is mounted a counterbalancing-weight 45. The weight is movable upon the beam and at opposite axial points is bored and provided with binding-screws 46, the inner ends of which bind upon the beam and thus maintain the weight rigidly thereupon.

Upon the upper ends of the standards, and at a point vertically above their overhanging front portions, there is provided a pair of opposite journal-boxes 47, and in the same there is mounted the transverse crank-shaft 48, the opposite terminals of which outside of the standards are each provided with large bevel-gears 49. The central portion of the crank-shaft is cranked, as at 50, and journaled thereupon is a knuckle-jointed link 51, provided at its lower end with a loosely-pivoted swivel 52, the lower end of which is centrally bored and threaded, as at 53.

The lower edge of the sliding head 9 is provided with a recess 55, the opposite walls of which are undercut or dovetailed, as at 56.

57 represents the stamp or former, and the same is similar in cross-section to the plan of the nut or washer to be formed. In this instance I have shown a stamper adapted to form a hexagonal nut, and the same, therefore, is hexagonal in cross-section. The upper portion of the stamp or former is removably connected to the head 9 and is centrally bored, as at 58. The head 9 is also vertically

perforated, as at 59, which perforation or opening agrees in location and size with that of the stamp. Mounted in the two openings—namely, that of the head and the stamp—and adapted for vertical reciprocation therein, is the punch 60. The punch 60 is of a length greater than the combined length of the head and stamp and has its upper end provided with a jam-nut 61, threaded on the same and entered in the lower threaded end of the swivel 52, so that said punch may be removed, and is also capable of a slight vertical adjustment. Brackets 62 are secured diagonally opposite each other at the outside of each of the standards 2, the outer ends of said brackets being provided with journal-boxes 63. In each pair of journal-boxes 63, at each side of the machine, there is mounted an inclined shaft 64, which shafts are each provided at their extremities with beveled pinions 65. The upper pair of pinions 65 mesh with and drive the bevel-gears 49, and the lower pair of pinions mesh with and are driven by the gears 21 and 31, mounted upon the power-shaft 19.

As before stated, the rear end of the lever 6 is upwardly and rearwardly disposed, and pivoted to the extremity of the same, as at 66, is the upper bifurcated end of a link 67, the lower end of which is provided with a box 68, which receives the crank portion of the shaft 19, and through the medium of the link the lever 6 is oscillated vertically. The lower front ends of the standards are continued beyond the overhanging portions, and mounted upon the same are opposite front and rear connecting sides 69, combining to form the bed 70 of the machine. The right-hand side of the bed, or rather that portion of the standard 2 forming the same, is recessed, as at 71, in its upper half, and formed upon the inner surfaces of the front and rear sides of the bed are ways 72, which ways are on a level with the bottom of the recess and are continued at the right-hand side of the bed by means of an inverted-L-shaped table 73, provided with opposite vertical flanges 74. The opposite or left-hand side of the bed has its lower half provided with a discharge-opening 75, and leading to the opening and from about the center of the opposite ways within the bed is an inclined discharge 76.

Mounted for sliding laterally upon the ways of the bed and upon the inverted-L-shaped extension thereof, or what was heretofore designated as the "table," is the die-carriage 77, the under portion of which is provided with two opposite longitudinally-disposed contact-surfaces 78, movable upon the opposite ways of the bed, and the upper surface of which is provided with a rectangular recess 79. Seated within the recess 79 and secured in its position by screws 80, inserted through the walls of the recess, is a die-plate 81, which, by reason of the screws, is removably secured in position, so that various forms of dies may be substituted for the same. The plate 81,

and also the carriage, is provided with a vertical opening 82, and surrounding said opening in the upper surface of the plate is a countersunk and in this instance hexagonal recess 83.

Superimposed over the bed is a bed or forming plate 84, which at its rear edge is secured to the front edges of the standards by L-shaped angle-plates 89, securely bolted to both the standards and plate, and at its front by double-L-shaped plates 90, securely bolted at their upper ends to the plate and at their lower ends to the front of the bed. The bed-plate or former is also provided near its center with an opening 91, in this instance of hexagonal shape, and exactly agreeing in size with the stamp 57, in the path of which the opening is arranged, and said opening is also coincident with the hexagonal countersunk recess in the die-plate directly under the same.

At the right-hand side of the machine there is located a pair of laterally-extending horizontal brackets 92, provided at their upper ends with journal-boxes 93. The inner ends 25 of the brackets are irregular, conforming to the edges of the base and feet of the machine, and are securely bolted to the standards 2 and to the feet of the standards, as at 94. Journalized in the brackets is a rock-shaft 95, 30 which extends from a point in rear of the standard to a point opposite the center of the bed, at which end it is provided with a rock-arm 96. The opposite end of the shaft is provided with a fixed yoke 97, and connecting 35 the terminals of the yoke is a threaded rod 98, jammed in position by means of opposite jam-nuts 99. The ends of the rod are squared, as at 100, to receive a wrench.

101 represents a block or slide having a 40 threaded perforation 102, through which the threaded rod passes, and by rotating said rod by means of an ordinary wrench applied to its squared end it will be apparent that the sliding block may be operated back and forth upon said 45 rod and within the yoke, so that said sliding block may be adjusted to or from the axial center of the rock-shaft. Projecting from the sliding block 101 is an arm 103, in the extremity of which there is pivoted, as at 104, 50 a vertically-disposed connecting-rod 105, the upper end of which is pivotally connected, as at 106, to a two-way connecting-shackle 107, the upper end being pivoted, as at 108, to a horizontal counterbalancing-lever 109, which 55 lever is pivoted, as at 110, at its inner end to an L-shaped bracket 111, bolted to the outer surface of the right-hand standard 2. This lever lies between the gear 31 and the cam-disk, and is provided with a laterally-projecting pin 112, carrying an anti-friction roller 113, which enters and travels within the continuous cam-groove of the disk.

The outer end of the die-carrying car or carriage is provided with a pair of bifurcated 65 lugs 114, and in the same there is pivoted, as at 115, a loose shackle 116, the opposite end

thereof being pivoted, as at 117, to the extremity of the rock-arm 96.

A pair of brackets 119^a are secured to the standard 2 at the right of the machine and 70 near the base, which brackets are provided with perforated bearing-lugs 118, in which is mounted a horizontal reciprocating locking-bar 119, provided at its end with a disk 120, from which there projects a locking-bolt 121. 75 From the back of the disk there projects rearwardly a guide-pin 122, the rear end of which is mounted for movement in guide-perforations 123, formed in the lugs 110, so that while the locking-bar 119 is free to reciprocate it is 80 maintained by the locking-pin against any rotary movement. A coiled spring 124 encircles the locking-bar between the disk at the end of the same and the front pair of brackets, thus normally forcing the locking-bar for 85 ward or to a locked position, and when the die-supporting car is within its bed the bolt of said locking-bar is maintained within a bolt-receiving opening 125 formed in the side of said car. 90

Vertically-opposite brackets 126 are secured to the right-hand standard 2, which brackets are provided with bearing-openings to receive a vertically-reciprocating rack-bar 127, which is therefore arranged at a right angle to the locking-bar 119. The rack-bar is provided near its upper end with a shoulder 128 and above said shoulder is cylindrical, and interposed between the shoulder and the upper bracket is a coiled spring 129, which normally 100 depresses the rack-bar so that its lower locking end rests upon the locking-bar 119, and when said locking-bar is withdrawn to the rear against the tension of its coiled spring said locking end engages a notch 130, formed 105 in the locking-bar, thus retaining the locking-bar in an unlocked position or out of engagement with the reciprocating die-carrying car. Above the rear end of the locking-bar there is secured to the standard 2 of the machine a laterally-projecting short bearing-standard 131, and upon the same there is pivoted an oscillating lever 132, the lower end of said lever being pivotally connected, as at 133, to the rear end of the locking-bar 119. 110 The upper or free end of the lever lies in the path of the friction-roller 34, projecting from the disk or plate 32, bolted to the beveled gear 31, and at each revolution of the fly-wheels 20 and their shaft said roller is 115 brought into contact with the upper end of the lever, throwing the same to the front and thus withdrawing the locking-bar against the tension of its spring, in which position it is locked by the rack-bar before described. 120

A bracket 134 is secured to the right standard 2, near its upper front portion, and in the same there is pivoted a bell-crank lever 135, the rear extremity of which is pivotally connected, as at 136, to a connecting-rod 137, 130 which depends at the side of the standard and is connected to the rear end of a horizontal

lever 138, mounted upon a bearing 139, projecting from the standard. The lever 138 is provided above its bearings with a vertically-disposed arm or branch 140, and secured to 5 said arm by a bolt 141 is a disk 142, which disk is journaled upon a bearing of the lever 138 and has a portion of its periphery toothed, as at 143, said teeth meshing with the teeth of the rack-bar 127 and serving to elevate 10 said rack-bar, so that its locking end will be disengaged from the notch in the locking-bar at each oscillation of the disk and its lever. The crank-shaft 48 at the right of the machine and between the bevel-gear 49 and the bearing for the shaft is provided with a disk 144, and adjacent to the periphery of said disk occurs the upper end of the bell-crank lever 135. The periphery of the disk is provided with a cam-lug 145, adapted to come into contact with the front upper end of the lever at 15 each revolution of the disk and thus oscillate the same upon its pivot, which movement, it will be observed, causes a depression of the opposite end of the bell-crank and the horizontal lever 138 and a partial rotation or oscillation of the toothed disk, which acts to elevate the rack-bar.

This being the construction of the machine, the operation of the same is as follows: A bar 30 of metal is introduced either by hand or any automatic feed over the opening in the forming-plate 84, and the machine being in operation the following movements of the parts will take place: Through the medium of the 35 counter-shaft, which is driven by any suitable motor connected by belting, the power-shaft 19 and its fly-wheels 20 are driven in the direction indicated by the arrows. A revolution of the power-shaft by reason of its cranked 40 portion elevates the rear end of the main lever 6, and the sector formed at the front end of said lever, meshing with the teeth of the bracket 11, secured to the rear face of the sliding head 9, causes said head to descend in 45 a positive manner, carrying with it the stamp 57, which, being arranged directly over the opening in the forming-plate 84, forces a blank of metal into the opening of said plate and down upon the countersunk recess of the die- 50 plate, which recess serves to mold or form the curved upper face or what is commonly known as the "crown" of the nut. The lower face or end of the stamp 57 being perfectly true and the power with which it is forced 55 down being very great, any jagged edges or upset portions of the metal blank will be stamped into the blank and destroyed, so that up to the present stage of the operation of the machine we have a perfectly-formed nut- 60 blank, the angles of which are perfectly true and of an exceedingly finished exterior. A further revolution of the power-shaft by its beveled gears 21 and 31, it will be observed, further turns or rotates the opposite inclined 65 shafts and the beveled gears 49, which latter rotate the crank-shaft 48 and bring the crank thereof to such a position as to lower the

punch beyond the lower end of the stamp. The punch descends and forms the usual opening in the nut at the same time that the 70 stamp is firmly seated and bearing upon the blank, so that any upsetting of the metal by reason of the punching operation is avoided, said stamp acting as a chuck in conjunction with the bed and forming-plate to securely 75 hold the blank in position. After the punching operation has taken place the sliding head is elevated, and with it the punch, the counterbalancing-weight 46 serving to aid in the elevation of the head, thereby lightening 80 the strain upon the machinery. At the time that the stamping of the blank and punching of the same take place, or rather previous thereto and during the same, it will be observed that the locking-pin of the locking-rod 85 138 is within the opening formed in the die-carrying car, so that the latter is absolutely prevented from any movement whatever during the operation of punching and forming, so that also the punching is perfectly true 90 with the axial center of the nut-blank. After the stamping and punching have taken place and the punch and stamp have been elevated above the nut the cam-disk 29 assumes such a position as to elevate the rock-shaft-operating lever 38, which lever is provided with a counterbalancing-weight 146. The elevating of the rear end of this lever, it will be observed, through the medium of the vertical connecting-rod, causes an oscillation of the 100 rock-shaft 95, which, through the medium of its rock-arm, withdraws the die-carrying car. This withdrawal of the die-carrying car laterally from the bed of the machine leaves the nut-blank thus formed in the opening of the 105 plate 84, so that said blank falls from said opening upon the inclined discharge within the bed. A further movement of the machine brings the cam-disk to such a position as to permit the weight 146 to depress the lever 110 and oscillate the rock-shaft 95 in a reverse direction ready for a subsequent repetition of the operation before described. After the punching and stamping operation and previous to the withdrawal of the die-carrying car 115 for the purpose of delivering the nut-blank the roller 34 on the disk 32 comes in contact with the upper end and rear face of the oscillating lever 132, which serves to throw said lever to the front and its lower end to the rear, 120 thus causing a withdrawal of the locking-bar from the die-carrying car and permitting the operation of withdrawing the car to take place. At the time that the bar is withdrawn it will be observed that the rack-bar is ready to engage the notch of the locking-bar, so that the latter is maintained in its retracted position 125 during the movement of the rock-shaft and the discharge of the nut-blank. When, however, the rock-shaft is at rest after a return of the die-carrying car, the cam-lug 145 is in position to strike the upper end of the bell-crank lever 135, thus causing a tilting of the lever, 130 a depression of its rear lower end, and an os-

cillation of the partially-toothed disk 144 and its horizontal operating-lever 138. Such movement, as before described, raises the toothed rack-bar, so that its lower end is disengaged from the notch of the locking-bar, and the latter is shot forward, so that its bolt enters the recess formed therefor in the die-carrying car, and said car is rigidly locked, and therefore in condition for a repetition of the stamping and punching operation heretofore described.

146^a represents a guide-plate, which extends transversely under the bed and forwardly under the head. The ends of the plate are upper turned, as at 147, and removably bolted, as at 148, to the sides of the head, and the transverse portion of the plate is recessed or provided with an opening 149, which agrees in contour with the stamp and serves as a guide for the same during its reciprocations. In removing the stamp the guide-plate is detached.

Having thus described my invention, what I claim is—

1. In a machine of the class described, the combination, with a bed provided with ways, of a die-carrying car mounted for reciprocation in the ways, means for reciprocating the car, and means for locking the same at the end of each reciprocation, substantially as specified.

2. In a machine of the class described, the combination, with a bed having ways, of a die-carrying car mounted upon the ways and having an opening, a spring-pressed bolt adapted to normally take in the opening, means for withdrawing the bolt from the opening, and means for locking the bolt against entering the opening and for subsequently unlocking said bolt, so as to enter the opening, substantially as specified.

3. In a machine of the class described, the combination, with the bed, of a reciprocating stamp, punch, and die-carrying car, the latter mounted on the bed under the stamp and punch, and mechanism for first depressing the stamp and secondly the punch, and subsequently elevating both and reciprocating the car, substantially as specified.

4. In a machine of the class described, the combination, with a bed, of a punch and stamp raised above the bed, a die-carrying car mounted for reciprocation on the bed, and means for depressing the stamp, and then the punch for unlocking the carriage and reciprocating the same, these operations being performed in the order named, substantially as specified.

5. In a machine of the class described, the combination, with opposite standards provided with a vertical bed having opposite ways, of a sliding head mounted in the ways, a removable centrally-bored stamp connected with the head, and a punch removably mounted for reciprocation within said bore, substantially as specified.

6. In a machine of the class described, the combination, with opposite standards pro-

vided at their front with a bed having opposite ways, of a sliding head mounted for movement in the ways, a stamp secured to the lower end of the same and having a central bore, a punch mounted in the bore and passing vertically through the head, means for lowering the head within its ways, a crank-shaft mounted above the head and having a central crank portion loosely connected with the punch, and means for operating the shaft, substantially as specified.

7. In a machine of the class described, the combination, with a vertical bed having opposite ways and a head carrying a stamp mounted for movement in the bed, of a punch mounted for movement in the head and stamp, and a crank-shaft journaled above the head and removably connected with the upper end of the punch and adapted to give the same independent movement of the head, substantially as specified.

8. In a machine of the class described, the combination, with a bed, a head mounted removably in the bed, centrally bored and having a centrally-bored stamp at the lower end of the same, of a crank-shaft journaled above the head, a loose connection depending from the centrally-cranned portion of the shaft, a swivel loosely connected at the lower end of said connection and having a threaded bore or socket at its lower end, and a punch mounted for reciprocation in the openings formed in the head and stamp and having its upper end threaded in the socket of the swivel, substantially as specified.

9. In a machine of the class described, the combination, with opposite standards terminating at their front ends in a bed, of a head mounted for sliding in the bed and adapted for the reception of a stamp, a lever pivoted in rear of the head between the standards and having its front end connecting with and adapted to actuate the head, and a power-shaft mounted in the standards and connected with and adapted to actuate the rear end of said lever, substantially as specified.

10. In a machine of the class described, the combination, with opposite standards forming a bed, a head mounted for sliding in the bed, and a toothed bracket secured to the rear face of the head, of a lever pivoted between the standards in rear of the head and having its front end terminating in a toothed sector for engaging the teeth of the bracket, and a power-shaft having a centrally-cranned portion loosely connected with the rear end of the lever and adapted to actuate the same, substantially as specified.

11. In a machine of the class described, the combination, with opposite standards terminating at their front ends in a bed, of a head mounted for sliding therein, a bracket secured to the rear face of the head and having a toothed flange provided with a curved slot, a main lever pivoted upon a shaft between the standards in rear of the head and terminating at its front end in a toothed sector

- meshing with the teeth of the flange, a block mounted for sliding in the slot of said flange, opposite straps secured to the sides of the lever and pivotally connected at their front 5 ends to the block, and a power-shaft journaled in the standards and having a centrally-cranked portion loosely connected to the rear end of the main lever, substantially as specified.
12. In a machine of the class described, the combination, with opposite standards terminating at their front in a vertical bed and a head mounted for sliding in the bed, of means for operating the head within the bed, a bearing-standard mounted at the upper end of the standards, a counterbalancing-lever pivoted in the bracket and having its front end bifurcated and spread, a counterbalanceing-weight mounted on the rear end of the lever, 15 and connecting-rods loosely jointed at their upper ends to the bifurcated ends of the lever and loosely connected at their lower ends to the upper end of the head, substantially as specified.
13. In a machine of the class described, a counterbalancing-lever, in combination with a circular counterbalanceing-weight having a radial opening for the reception of the lever and opposite axial threaded openings and opposite set-screws mounted in said openings and having their inner ends binding upon the lever, substantially as specified.
14. In a machine of the class described, the combination, with opposite standards terminating at their front ends in a vertical bed and a head mounted for sliding in the bed, of a shaft mounted transversely in the standards and a lever pivotally mounted on the shaft, the front end of said lever engaging and 30 actuating the bed and in rear of its shaft being upwardly and rearwardly bent, a power-shaft journaled in the rear end of the standards and having a central crank portion located under the rear end of the lever, and a link or shackle loosely connected with the crank portion of the shaft and with the rear end of the lever, whereby a rotary motion of the shaft imparts an oscillatory motion to the lever, substantially as specified.
15. In a machine of the class described, the combination, with opposite standards provided with guides and a reciprocating punch mounted in the guides, of a crank -shaft loosely connected with the punch and provided at its opposite ends with bevel-gears, opposite inclined shafts mounted in bearings at each side of the standards and provided at their opposite ends with pinions, the upper ones of which mesh with the bevel-gears, 45 and a power-shaft journaled in rear of the inclined shafts and provided at opposite sides with beveled gears engaging the lower opposite pinions of the inclined shafts, substantially as specified.
16. In a machine of the class described, the combination, with opposite standards, a re-
- ciprocating punch, a crank-shaft loosely connected therewith, and beveled gears mounted on the ends of the crank-shafts, of a counter-shaft adapted to be connected to a motor, a gear mounted on the shaft, a power-shaft journaled above the counter-shaft and having a gear meshing with that of the counter-shaft, opposite beveled gears and fly-wheels mounted on the power-shaft, and opposite inclined short shafts terminating at their ends in beveled pinions, the lower pinions engaging the beveled gears of the power-shaft, and the upper pinions the beveled gears of the crank-shaft, substantially as specified.
17. In a machine of the class described, the combination, with a bed having opposite ways and an inclined discharge arranged between the ways, of a die-carrying car mounted for movement on the ways over the discharge, a stationary forming-plate superimposed or arranged over the car and having an opening vertically above the discharge, and means for withdrawing the car from over the discharge, substantially as specified.
18. In a machine of the class described, a die-carrying car the upper surface of which is provided with a recess, in combination with a die-plate seated in the recess, substantially as specified.
19. In a machine of the class described, the combination, with a die-carrying car, of a die-plate removably mounted in the recess, substantially as specified.
20. In a machine of the class described, the combination, with a car having a recess and an opening, of a die-plate snugly fitting the recess and provided with a countersunk crown-forming recess and a concentric opening registering with the one in the car, substantially as specified.
21. In a machine of the class described, the combination, with a bed and a car mounted for movement thereon, of a rock-shaft journaled at one side of the bed and having one end loosely connected with the car, a lever pivoted to one side of the frame of the machine, a cam-disk mounted on a shaft and having its groove engaged by a projection on the lever, and a connecting-rod connecting said lever with the rock-shaft, whereby a rotation of the cam-disk causes an elevation of the lever and a partial rotation of the rock-shaft, substantially as specified.
22. In a machine of the class described, the combination, with a bed provided with ways and a car mounted for reciprocation on the ways, of a rock-shaft mounted in bearings at one side of the bed, a rock-arm connected with one end of the shaft and loosely connected by a swivel to the end of the car, a yoke connected to the opposite end of the shaft and provided with an adjustable slide, a power-shaft, a disk having a cam-groove mounted on the same, a lever pivoted to the machine and having a projection riding in the groove of the disk, and a connecting-rod

- loosely connecting the rear end of the lever with the sliding block, substantially as specified.
23. In a machine of the class described, the combination, with a rock-shaft connected at its forward end to and adapted to actuate a die-carrying car and provided at its lower end with a yoke, of a threaded rod mounted in the yoke and squared at its ends, a sliding block having an arm mounted on the rod, a power-shaft journaled in the frame above the rock-shaft, a disk having a cam-groove mounted on the shaft, a pivoted lever having a projection engaging the groove, a shackle pivoted to the rear end of the lever, and a connecting-rod pivoted in the shackle and at its lower end to the arm of the sliding block, substantially as specified. 70
24. In a machine of the class described, the combination, with a bed and a reciprocating die-carrying car, of a spring-pressed locking-bolt mounted for reciprocation at one side of the car and adapted to be shot into an opening in the car, a lever pivoted above the bar and at its lower end to the bar and a revolute disk mounted on a shaft above the lever and having a projection adapted to strike the same at its upper end, so as to cause a retraction of the bolt, substantially as specified. 75
25. In a machine of the class described, the combination, with a bed having opposite ways and a reciprocating die-carrying car mounted upon the ways, of horizontally-aligning bearing-brackets secured to the frame of the machine at one side of the car, a locking-bar mounted in the brackets for reciprocation and terminating at its front end in a disk carrying a locking-pin, a spring interposed between said disk and an adjacent bracket, a lever pivoted at its lower end to the rear end of the bar and to bearings above the bar, and means for intermittently operating said lever, substantially as specified. 80
26. In a machine of the class described, the combination, with a reciprocating car having a bolt-receiving opening, of opposite bearing-brackets located at one side of the car, a reciprocating bar mounted in the brackets and terminating at its front end in a disk provided with a bolt and at its rear end with a guide-rod, the opposite end of which takes into a perforation in the bracket, and means, substantially as specified, for reciprocating the bar. 85
27. In a machine of the class described, the combination, with a reciprocating carriage, a reciprocating bar for locking the same, a spring for pressing the bar to a locked position, and means for retracting the bar, of a bolt arranged for reciprocation above the locking-bar and having its lower end adapted to engage a notch in said locking-bar, a coiled spring arranged upon the bolt for depressing the same, and means for raising the bolt out of connection with the bar, substantially as specified. 90
28. In a machine of the class described, the combination, with a reciprocating carriage, a reciprocating bolt for locking the same, a spring for pressing the bolt to a locked position, and a lever for retracting the bolt against its spring, of a toothed bolt mounted in brackets above the bar and adapted at its lower end for engaging a notch in said bar, a spring for depressing said bolt, a toothed disk mounted pivotally and engaging the teeth of the bolt, a lever for operating the disk, whereby the latter elevates the bolt out of connection with the rod, and means for operating the lever, substantially as specified. 95
29. In a machine of the class described, the combination, with a reciprocating carriage, a reciprocating bar for locking the same, a spring for pressing the bar to a locked position, and a lever for operating the bar in a reverse direction, of a toothed bolt mounted for reciprocation above the bar and adapted at its lower end to engage a notch in the same, a spring for depressing the bolt, an oscillating disk partially toothed to engage the teeth of the bolt, a pivoted lever secured to the disk, a bell-crank lever pivoted above the disk, a connecting-rod loosely pivoted to the lower end of the bell-crank and to the rear end of the disk-operating lever, a shaft and means for rotating the same arranged above the bell-crank, and a disk mounted on the shaft and having a cam-lug for coming in contact with and operating the bell-crank, substantially as specified. 100
30. In a machine of the class described, the combination, with the opposite standards terminating in an overhanging portion forming a vertical bed and a head mounted for sliding in the bed and provided with a removable stamp, of a guide-plate extending under the bed and head and having an opening agreeing in contour with the stamp and removably connected with the bed, substantially as specified. 105
31. In a machine of the class described, the combination, with a bed and forming plate, of a reciprocating stamp and a reciprocating punch, means for lowering the stamp and then the punch, then raising the punch and afterward the stamp, whereby said stamp serves to hold the nut during the operation of punching, and a die-carrying car mounted for reciprocation in ways of the bed below the punch and the stamp and at right angles to the same, substantially as specified. 110
32. In a machine of the class described, the combination, with a bed having ways, of a die-carrying car mounted upon the ways and having an opening, a spring-pressed bolt adapted to normally take in the opening, and means for withdrawing the bolt from the opening, substantially as specified. 115
33. In a machine of the class described, the combination of the horizontally-reciprocating die-carrying car 77, the vertically-reciprocating stamp 57, and the vertical punch 60, reciprocating through the stamp, the parts being so timed in their movements that the 120
- 77, the vertically-reciprocating stamp 57, and the vertical punch 60, reciprocating through the stamp, the parts being so timed in their movements that the 125
- 77, the vertically-reciprocating stamp 57, and the vertical punch 60, reciprocating through the stamp, the parts being so timed in their movements that the 130

stamp serves to hold the nut during the operation of punching, as set forth.

34. In a machine of the class described, the combination, with the horizontally-reciprocating die-carrying ear 77, of the vertically-reciprocating stamp 57, a weighted lever having pivoted links from which the stamp is suspended, and the vertical punch 60, reciprocating through the stamp, the parts being so timed in their movements that the stamp serves to hold the nut during the operation of punching, as set forth.

35. In a machine of the class described, the combination, with the horizontally-reciprocating die-carrying ear 77, of the spring-pressed

bolt to lock the ear when it is in place, which bolt is withdrawn by the movement of the machine, the vertically-reciprocating stamp 57, and the vertical punch 60, reciprocating through the stamp, the parts being so timed in their movements that the stamp serves to hold the nut during the operation of punching, as set forth.

In testimony that I claim the foregoing as my own I have hereto affixed my signature in presence of two witnesses.

GEORGE JONATHAN FORREY.
